(57) **CLAIM**

We claim the ornamental design for a trailer for mobile turbomachinery electric power generation, as shown and described.

DESCRIPTION

FIG. 1 is a perspective view of a trailer for mobile turbomachinery electric power generation.

FIG. 2 is a top view of the trailer of FIG. 1.

FIG. 3 is a bottom view of the trailer of FIG. 1.

FIG. 4 is left side view of the trailer of FIG. 1.

FIG. 5 is right side view of the trailer of FIG. 1.

FIG. 6 is a rear view of the trailer of FIG. 1; and,

FIG. 7 is a front view of the trailer of FIG. 1.

The elements shown in broken lines are included for the purpose of illustrating environment and form no part of the claimed design.
